BY Richard Brown,

ATTORNEY

UNITED STATES PATENT OFFICE.

ALBIN WICKLUND, OF BIWABIK, MINNESOTA.

PENCIL-SHARPENER.

1,284,009.

Specification of Letters Patent.

Patented Nov. 5, 1918.

Application filed December 20, 1917. Serial No. 208,118.

To all whom it may concern:

Be it known that I, ALBIN WICKLUND, a citizen of the United States, residing at Biwabik, in the county of St. Louis and State of Minnesota, have invented certain new and useful Improvements in Pencil-Sharpener, of which the following is a specification.

This invention relates to an improvement in pencil sharpeners, and it is a purpose thereof to provide a device of this character which is of small and compact form, and which is so constructed that in one adjustment of the parts it can be used as a safety fastener or clip to retain a pencil in a pocket.

A further object is to provide a structure in which the adjustment can be readily and expeditiously made to adapt the device for use as a pencil sharpener or as a safety clip, and in which these adjustments will be held until the parts are manually reset.

Yet another object is to provide a knife portion which is shaped at one end to provide cutting edges by which a pencil will be sharpened, and at the opposite end is formed into a gripping finger to be used when the parts are set for application of the structure as a safety clip or fastener, the arrangement of the parts being such that when the knife member is set for sharpening a pencil, the gripping finger portion is presented for use as a handle in turning the pencil sharpener, while when the parts are set for use of the structure as a safety clip force is exerted upon the end of the knife having the cutting blade formed in conjunction therewith to force the clamping finger down against the edge of the pocket to which the pencil having the safety clip thereon is fitted.

With the above and other objects in view, which will be in part described, and in part understood from the specification, drawings, and claims, my invention consists in certain novel features of construction and combination of parts which will be hereinafter more fully set forth.

In the drawings:—

Figure 1 is a view in elevation of the device of my invention with the parts adjusted for use in sharpening a pencil and illustrating a pencil fitted thereto;

Fig. 2 is a longitudinal sectional view

through the structure with the parts set as shown in Fig. 1;

Fig. 3 is a view similar to Fig. 2 but showing the parts set for use of the device as a safety fastener;

Fig. 4 is a transverse sectional view taken on the line 4—4 of Fig. 1;

Fig. 5 is a view in section on the line 5—5 of Fig. 1;

Fig. 6 is a transverse sectional view on the line 6—6 of Fig. 1 and looking in the direction indicated by the arrow;

Fig. 7 is a sectional view on the line 7—7 of Fig. 3; and,

Fig. 8 is a fragmentary detail view showing a modification which might be made in the pencil sharpening member.

Fig. 9 is an inverted perspective view of the sharpening member.

A tubular body 1, which is preferably of a resilient metal and which is made of a size to receive a pencil, is slotted through longitudinally at one side and adjacent one end 75 as indicated at 2, this end being preferably slightly contracted so that as a pencil is fitted through the tubular body in the manner shown in Fig. 3, frictional bearing will be exerted thereagainst and the body portion will be retained against slipping from the pencil, and against casual displacement therefrom. A combination sharpening and clip member 3 has a foot ring 4 fitted through a transverse bore formed in the middle portion thereof and this foot ring 4 is contracted into a groove 5 formed peripherally around the middle portion of the tubular body 1 so that the combined sharpener and clip member 3 is pivotally mounted 90 upon the tubular body portion and adjacent the slotted opening 2 thereof.

On a sharpening end, the member 3 is grooved on the inner side so that cutting edges are provided as indicated at 6, and at 95 the remaining end the member 3 is made smooth and rounded so that when the device is used as a safety clip the clothing of the user will not be torn or damaged. Slit collars 7 and 8 are mounted around the body portion 1 on opposite sides of the foot ring 4, it however being understood that while these slit collars are not set or fixed upon the body portion, the adherent flexibility there-

2
of will cause the same to be retained in fixed adjustment upon the body portion. The opening of the slit collars is of substantially the same width as the width of the 5 slotted opening 2, and when the collars are set in certain adjustments the slotted opening 2 is entirely open and unobstructed, whereas in other adjustments of the slit collars their width is interposed across this 10 slotted opening.

In the use of the device as a safety clip, the slit collar 8 is adjusted so that it does not offer any obstruction under one clip end 9 of the member 3, while the slit collar 7 is 15 turned to bring the body portion thereof beneath the knife end 10 of this member, in which position the slit collar 7 forces the clip end 9 of the member 3 down toward the collar portion of the body 1. As has been 20 stated, the body portion 1 is made of sufficient size that a pencil will be received therein and the natural resiliency of this body portion will sufficiently hold the pencil within the bore thereof. When a pencil is 25 placed within a pocket, the clip end 9 of the member 3 will be caught over the top edge of the pocket to clamp the same against the body portion 1 and in consequence the device will act as a safety clip or attach to secure 30 the pencil against casual displacement from the pocket.

When the structure is to be used as a pencil sharpener, the slit collar 7 is turned to bring the opening thereof into register with 35 the slotted opening 2 of the body member 1 and then the member 3 is swung to move the knife end 10 thereof into the bore of the body member or portion 1, it of course being understood that the pencil has been with- 40 drawn from the slotted end thereof. The collar 7 is now given further turning movement to bring a solid portion thereof over the outer side of the knife end of the member 3, and the slit collar 8 is adjusted to bear 45 on the under side of the shoulder 11 pro- vided on the clip end 9 of this member so that the knife end is thus positively held and forced to be inclined into and toward the open end of the tubular body portion 1, substantially after the manner shown in 50 Figs. 1 and 2. As a pencil is inserted within the unobstructed end of the body portion and is given turning movement after being brought into contact with the knife 55 end 10 of the member 3, the cutting edges 6 will sink into the wood of the pencil and in consequence the same will be cut away to sharpen the pencil.

In Fig. 8 I have shown a slightly modified construction of the knife end of the member 3, and as is here illustrated, the inner side of the knife end is roughened as indicated at 12, after the manner of a file or rasp, so that as a pencil is brought there- 60 against and is turned, the wood of the pencil

will be cut away and the pencil will be properly sharpened.

From the above it will be seen that I have provided a structure which is made up of comparatively few parts and which could be 70 simply and inexpensively manufactured, but which is of such character that in either of the uses for which the same is intended, most efficient results are accomplished.

While, in the foregoing, I have described 75 a specific embodiment of the present invention, it is to be understood that in practice, I do not limit myself to such specific details but may resort to any practical modifications falling within the scope of the invention 80 as defined in the appended claims.

I claim:

1. A pencil sharpener including in combination with a tubular body portion having a slotted opening formed in one side thereof 85 transversely and opening through one end, a combined sharpening and clip member having a cutting formation at one end thereof, a split ring by which the combined member is pivotally mounted in its middle 90 portion upon the body portion to have the cutting formation thereof over the slotted opening, and slit collars mounted on the body portion on opposite sides of the connection of the split ring therewith. 95

2. A pencil sharpener comprising the body provided with a slotted opening formed in one side thereof, a combined sharpener and clip member pivotally mounted upon said body, said sharpening 10 and clip member provided with cutting edges formed upon one face thereof, said cutting edges adapted to be swung within said slotted opening for contact with a pencil extending through said body, and means 10 for engaging the under face of said combined sharpener and clip member for locking the same in a swung position.

3. A sharpener of the class described comprising a body provided with a slotted opening formed in one side thereof, a combined sharpener and clip member, a securing ring pivotally supporting said sharpener and clip member upon said body, and a plurality of split spaced rings carried by said body 11 and adapted to have their split portions brought into registration with said slotted opening, said combined sharpener and clip member provided with step portions formed upon the under face thereof adapted to be 11 engaged by one of said split collars for holding said combined sharpener and clip member in a swung and operative position.

4. A pencil sharpener comprising a body provided with a slotted opening formed 1 therein, a plurality of spaced split rings mounted upon said body and capable of being rotated thereon, said spaced rings adapted to have their slotted portions register with said slotted opening, a combined 1

sharpener and clip member pivotally mounted upon said body and adapted to swing against said opening as the slotted portion of said body registers with the split portion 5 of said rings, and said split rings being adapted to have their split portions alternately register with said slotted portion in said body for alternately holding said com-

bined sharpening and clip member in a sharpening and clamping position.

In testimony whereof I affix my signature 10 in presence of two witnesses.

ALBIN WICKLUND.
